CLAIM

The ornamental design for a bedside table, as shown and described.

DESCRIPTION

FIG. 1 is a front perspective view of a bedside table, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view showing the bedside table in an open state.

The broken lines in the drawings illustrate the portions of the bedside table, which form no part of the claimed design.
